Summit Ave., Union City, N.J.

Filed Mar. 5, 1963, Ser. No. 73,815

Term of patent 14 years

(Cl. D48—20)

FIG. 1 is a side view of a portable lamp embodying our new design.

FIG. 2 is a top view of said lamp; and

FIG. 3 is a perspective view of the lamp with a fragmentary chair shown in broken lines for illustrative purposes only.

The dominant features of our design reside in the portions shown in full lines.

We claim:

The ornamental design for a portable lamp, substantially as shown and described.
